CLAIM

The ornamental design for a tool to remove P.C.V. screen from 1986-1990 ford cars, as shown and described.

DESCRIPTION

FIG. 1 is a front elevational view of the tool to remove P.C.V. screen from 1986-1990 ford cars showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

In FIGS. 1-4, the device is shown broken away to indicate indeterminate length.
